UNITED STATES PATENT OFFICE.

JOHN ELSER, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

BY-PASS GAS-COCK.

1,140,026.

Specification of Letters Patent. Patented May 18, 1915.

Application filed February 27, 1915. Serial No. 10,933.

To all whom it may concern:

Be it known that I, JOHN ELSER, a citizen of the United States, residing at Gloucester City, in the county of Camden and State of 5 New Jersey, have invented a new and useful Improvement in By-Pass Gas-Cocks, of which the following is a full, clear, and exact description, reference being had to the accompanying drawing, forming part of this 10 specification, in which—

Figures 1 and 2 are end and side elevations, illustrating the preferred form of gas cock embodying my invention; Fig. 3 is a vertical sectional view of the same; and 15 Figs. 4, 5 and 6 are detail views hereinafter more fully described.

My invention has relation to bypass gas cocks of the one-chain type, and is designed to provide a gas cock of this type having 20 means of simple, novel and efficient character for holding the cock plug in position when the actuating lever moves back to its normal position after each pulling operation.

25 Referring to the accompanying drawings, in which I have shown a preferred form of my invention, the numeral 2 designates a gas pipe having a valve fitting 3, in which is mounted a valve plug 4, which is of the 80 usual rotary type, with a gas port 5 therethrough.

6 is an indicator, which is rigidly secured to the outer projecting end of the stem 7 of this plug.

35 8 is an actuating lever which is mounted to rotate on the stem 7, and is formed about its axis of rotation with an outwardly directed clutch portion 9, having clutch teeth or projections 10, adapted to engage the 40 stems 6^a of the indicator 6.

11 is a spring interposed between the lever 8 and the fitting 3, and normally holding the lever outwardly in position to cause its engagement with the indicator. One end of 45 this spring is connected to the lever 3, as indicated at 12, and the other end is fastened to a pin or projection 14 on the fitting 3. The spring is wound in such a direction as to have its tension increased when 50 the lever 8 is pulled downwardly.

The numeral 13 designates a small auxiliary spring wound about the inner end portion of the stem 7 and having a free end extending upwardly and secured to the projecting pin 14, which also acts as a stop to

limit the upward movement of the actuating lever 8. This spring 13 is wound in the reverse direction to the spring 11.

15 designates a flexible pull device of any suitable character, which is attached to the 60 lever 8.

16 designates the bypass or pilot light connection which enters the valve fitting 3, above the turning plug in the usual manner.

The operation will be readily understood. 65

A downward pull on the connection 15 moves the lever 8 in a downward direction, thereby causing two of its clutch teeth to engage and operate the indicator, the spring 11 being meanwhile placed under increased 70

tension. As soon as the pull chain is released, the spring 11 acts to immediately return the lever 8 to its normal position. During this return movement, however, the valve plug remains stationary, owing to the 75 increased friction of the spring 13, which winds upon the stem 17, during the return movement of the lever 8, to a sufficient extent to act as a brake. In this manner, the valve or cock plug is always turned in one 80 direction only by the operation of the pull connection, and is always left either in its fully open or fully closed position. The device forms a very simple and effective one 85 for the purpose.

I claim:

1. A gas cock having a rotating valve plug, a clutch lever loosely mounted on the stem of said valve and having an operating connection therewith in one direction of 90 movement, a spring for returning the lever to normal position after each operation, and a braking device arranged to prevent backward movement of the plug and being inoperative in the other direction, substantially as described.

2. A gas cock comprising a rotary valve plug, a clutch lever for actuating the plug in one direction, a spring for returning the lever to normal position after operation, 100 and a braking device connected to the valve plug and arranged to be put under increased tension by any reverse movement of the plug, substantially as described.

3. A gas cock comprising a rotary valve 105 plug, a clutch lever for actuating the plug, a spring for returning the lever to normal position after each operation, and a braking spring coiled upon the stem of the plug in a reverse direction to the first named 110

spring and in engagement with the periphery thereof, said spring being inoperative when the plug is rotated in one direction and adapted to clamp the plug and restrain it from movement in the other direction, substantially as described.

4. A gas cock having a rotary valve plug, a device for turning said plug in one direction, a spring for returning said device to normal position after each operation, and another and reversely operating spring in engagement with the periphery thereof for preventing reverse movement of the plug, substantially as described.

15 5. A gas cock having a rotating valve plug, a clutch lever loosely mounted on the stem of said plug and having an operating

connection therewith in one direction of movement, a spring for returning the lever to normal position after each operation, and a helical spring surrounding the stem of the plug, one end of said spring being secured against movement, said spring being arranged to permit the plug to move freely in one direction and to grip the plug and restrain it from movement in the other direction; substantially as described.

In testimony whereof, I have hereunto set my hand.

JOHN ELSER.
